(57) **CLAIM**

The ornamental design for a display screen or portions thereof with graphical user interface, as shown and described.

DESCRIPTION

FIG. 1 is a front view of the display screen or portions thereof with graphical user interface showing my new design; and,

FIG. 2 is a front view thereof, shown in an alternate environment.

The outer broken lines show the display screen and form no part of the claimed design. The broken lines of the graphical user interface form no part of the claimed design.
